(57) **CLAIM**

An ornamental design for a veterinary oxygen mask, as shown and described.

DESCRIPTION

FIG. 1 is a front perspective view of the veterinary oxygen mask.

FIG. 2 is a front view of the veterinary oxygen mask.

FIG. 3 is a back view of the veterinary oxygen mask.

FIG. 4 is a top view of the veterinary oxygen mask.

FIG. 5 is a bottom view of the veterinary oxygen mask.

FIG. 6 is a right side view of the veterinary oxygen mask.

FIG. 7 is a left side view of the veterinary oxygen mask; and,

FIG. 8 is a back perspective view of the veterinary oxygen mask.

The broken lines in the drawings depict portions of the veterinary oxygen mask that form no part of the claimed design.
